(57) **CLAIM**

The ornamental design for a speaker tower, as shown and described.

DESCRIPTION

FIG. 1 is a front perspective view of a speaker tower showing my new design;

FIG. 2 is a front view of the speaker tower shown in FIG. 1; FIG. 3 is a rear view of the speaker tower shown in FIG. 1; FIG. 4 is a left side view of the speaker tower shown in FIG. 1;

FIG. 5 is a right side view of the speaker tower shown in FIG. 1;

FIG. 6 is a top view of the speaker tower shown in FIG. 1; FIG. 7 is a bottom view of the speaker tower shown in FIG. 1; FIG. 8 is a top perspective view of the speaker tower shown in FIG. 1; and,

FIG. 9 is a front perspective view of the speaker tower shown in FIG. 1 with the front surface shown as removed. The broken line showing of the buttons, docks, feet, support bar and back circular opening are included for the purpose of illustrating portions of the speaker tower and forms no part of the claimed design.

1 Claim, 6 Drawing Sheets
